INTERCOMMUNICATING SYSTEM

Angelo Montani, Woodhaven, N. Y., assignor to
 Automatic Electric Laboratories, Inc., Chicago,
 Ill., a corporation of Delaware

Application September 24, 1945, Serial No. 618,351

8 Claims. (Cl. 179—1)

1

The present invention relates in general to intercommunicating systems, and in particular to an improved arrangement for preventing feedback or singing in such systems.

Numerous methods have been proposed for eliminating feedback in loudspeaking intercommunicating systems. One of the most commonly used methods involves the provision of "talk-listen" keys at each station, which keys are alternately operated to successively condition the system for transmission in opposite directions. The principal objections to the use of "talk-listen" keys is that they prevent free use of the speaker's hands for taking notes or searching through records during a conversation, and that the conversation is unnatural in that the listener is generally unable to interrupt the speaker.

It is accordingly an object of the present invention to obviate the use of "talk-listen" keys by providing means for rendering the transmitting means and the receiving means at each station alternately effective at a low frequency rate so as to successively condition the system for transmission in opposite directions.

A feature of the invention is the provision of a common low frequency oscillator for rendering the transmitting and receiving means at each station alternately effective, the low frequency current produced by said oscillator being transmitted from one station to the other over a speech signal channel.

The invention may best be understood from the following description taken in conjunction with the accompanying drawing which schematically illustrates an intercommunicating system embodying the invention.

Briefly described, the invention comprises the provision, at each station of an intercommunicating system, of thermionic tubes which are associated with the transmitting and receiving means thereat so as to render them effective selectively. A low frequency oscillator is provided at one station for controlling said thermionic tubes, a portion of the output of said oscillator being transmitted to the other station to control the thermionic tubes thereat over a signal channel which is also used to transmit speech signals between the stations in either direction.

Referring now to the drawing, there are shown two stations, A and B, which are interconnected by a two conductor line 1. A two way amplifier 2, which may be a Type 21 repeater, is inserted in line 1. Station A includes a transmitter or microphone 3, an associated thermionic tube 4, a receiver or loudspeaker 5, an associated

2

thermionic tube 6, batteries 7 and 12, transformers 8 and 9, filters 10 and 11, and a low frequency oscillator 23. Station B is similarly equipped with the exception that no oscillator is provided thereat.

In the absence of the thermionic tubes 4 and 6, and the corresponding tubes 14 and 16 at station B, singing will usually occur in such a system when there is acoustic coupling between the transmitters and receivers at each station. Thus a signal produced by transmitter 3 will be impressed on the left end of line 1 through transformer 8 and filter 10 and will appear in amplified form at the right end of line 1. The amplified signal is impressed on receiver 15 through filter 20 and transformer 18. When the amplified signal is reproduced by the receiver 15 a corresponding signal will be produced by transmitter 13 due to the acoustic coupling existing therebetween. The signal produced in transmitter 13 will be amplified by the amplifier 2 and the amplified signal will be reproduced by receiver 5. Due to the acoustic coupling between receiver 5 and transmitter 3, the sound waves produced by receiver 5 will produce a new signal in transmitter 3 which may reinforce the original signal and result in sustained oscillations if the net gain around the loop is more than the net loss. The frequency at which such oscillations or howling occurs is determined by the length of the acoustic paths between the transmitters and receivers and the electrical phase shift around the loop. It may be noted that a similar condition will occur when the transmitter of each station is coupled to the receiver of the other station over an individual signal channel.

The above described difficulty is overcome when "talk-listen" keys are provided since the transmitter and receiver at either station are never rendered effective simultaneously. Applicant has discovered that if the transmitter 3 and receiver 15 are intermittently rendered effective at a low frequency rate, say thirty times per second, and transmitter 13 and receiver 5 are intermittently rendered effective during the intervals when transmitter 3 and receiver 15 are ineffective, normal conversation can be carried on between stations A and B. In order to avoid the production of parasitic frequencies the transmitters and receivers must be enabled and disabled gradually rather than instantaneously.

The use of mechanical switching devices is therefore impractical. By employing thermionic tubes with suitable potentials applied to the con-

trol electrodes thereof, a smooth yet rapid enabling and disabling of the transmitters and receivers is effected. Thus at station A, the thermionic tube 4 is connected in series with transmitter 3 and transformer 8 to battery 7. If the transmitter 3 is of the carbon type, the battery 7 serves the dual function of furnishing a source of anode potential for tube 4 and of supplying energizing current to the transmitter 3. Thermionic tube 6 is connected in series with receiver 5 and transformer 8 to battery 7. The control electrodes of tubes 4 and 6 are connected to opposite ends of the secondary winding of transformer 9. The midpoint of this secondary winding is connected to the cathodes of tubes 4 and 6 through a biasing battery 12. A low frequency oscillator 23 is connected to the primary winding of transformer 9. The biasing potential applied to the control electrodes of tubes 4 and 6 by battery 12 has a value such that each tube normally has a nominal anode impedance. The potentials induced in the secondary winding of transformer 9 by oscillator 23, which potentials are impressed on the control electrodes of tubes 4 and 6 180° out of phase, causes the anode impedances of these tubes to alternately increase and decrease at a low frequency rate. When the anode impedance of tube 4 is low the transmitter 3 is rendered effective to impress speech signals on line 1 corresponding to sound waves impressed on the transmitter. During the time that the anode impedance of tube 4 is low, the anode impedance of tube 6 is high, thereby rendering the receiver 5 ineffective to reproduce signals, either incoming from line 1 or produced by transmitter 3, which appear thereacross in series with tube 6. During a succeeding half-cycle of the voltage wave produced by oscillator 23, the anode impedance of tube 4 is high thereby rendering transmitter 3 ineffective. At the same time the anode impedance of tube 6 is reduced to a low value to render receiver 5 effective to reproduce signals appearing across the terminals of transformer 8. A portion of the output of oscillator 23 is transmitted through the low pass filter 11, over the left portion of line 1, through amplifier 2, over the right portion of line 1, and through low pass filter 21 to the primary winding of transformer 19. The secondary winding of transformer 19 is connected to the control electrodes of tubes 14 and 16 so that tubes 4 and 16 simultaneously render transmitter 3 and receiver 15 effective, and tubes 6 and 14 simultaneously render receiver 5 and transmitter 13 effective during the intervals when transmitter 3 and receiver 15 are ineffective. The high pass filters 10 and 20 and the low pass filters 11 and 21 are provided to isolate the speech waves and the low frequency control wave at each station. This is possible because the lowest frequency signal which must be transmitted for satisfactory reproduction of speech is of the order of 150 cycles per second.

The use of a low frequency for rendering the system alternately effective to transmit signals in opposite directions is preferable to a frequency above the audible range because of the difficulty in maintaining synchronism between the keying tubes at the two stations due to increasing phase shift in the signal channel, amplifier, and filter networks, with increasing frequency. If a separate conductor is employed between the two stations to transmit the control wave derived from oscillator 23 to station B, the difficulties produced by phase shift in the

filter networks and amplifier may be circumvented, thereby enabling the use of a control wave having a frequency above the audible range.

While a particular embodiment of the invention has been illustrated, it should be understood that numerous modifications may be incorporated therein without departing from the true spirit and scope of the invention as defined in the subjoined claims.

10. What is claimed is:

1. In an intercommunicating system, two stations, a two-way signal channel between said stations, voice transmitting and voice receiving means at each of said stations coupled to said channel, a pair of vacuum tubes at each of said stations for alternately rendering effective the transmitting and receiving means thereat, a source of alternating current continuously connected to said channel, and circuit arrangements for impressing control voltages derived from said source on the grid electrodes of all of said tubes so as to successively at a predetermined rate condition the system for voice transmission in opposite directions between said stations over said two-way channel.

2. An intercommunicating system as claimed in claim 1 wherein the frequency of said source is less than that of the lowest frequency component in the voice signals transmitted between said stations.

3. An intercommunicating system as claimed in claim 1 wherein said source of alternating current is located at one of said stations, and said circuit arrangements include provisions for transmitting said control voltage over said signal channel to the other of said stations.

4. In an intercommunicating system, two stations, voice transmitting means and voice receiving means at each of said stations, conductors extending between said stations to enable two-way voice communication therebetween, a low frequency source of alternating current at one of said stations, circuit arrangements for continuously transmitting current from said low frequency source to the other station over said conductors, filters individually associated with each of said stations for isolating said low frequency source from said voice transmitting means and said voice receiving means, and means at each of said stations controlled by voltages derived from said low frequency source for successively at a predetermined rate conditioning the system for voice transmission over said conductors in opposite directions between said stations.

5. In an intercommunicating system, two stations, a line extending between said stations, a two-way amplifier connected in said line between said stations, a transmitter and a receiver at each of said stations, a pair of vacuum tubes at each of said stations for selectively coupling the transmitter and receiver thereat to said line, a source of alternating current continuously connected to said line at one of said stations and to said line at the other station through said amplifier, and means for impressing control voltages derived from said source on the grid electrodes of all of said tubes so as to successively at a predetermined rate condition the system for voice transmission in opposite directions between said stations.

6. In a telephone system, a station including a transmitter and a receiver, a line extending from said station over which two-way voice communication with another station is effected, a pair of thermionic tubes, one of said tubes being associ-

ated with said transmitter so as to control the effectiveness thereof, the other of said tubes being associated with said receiver so as to control the effectiveness thereof, and means comprising a source of alternating current continuously coupled to said tubes for impressing alternating control voltages on the grid electrodes of said tubes in phase opposition corresponding to the frequency of said source, whereby said transmitter and receiver are alternately rendered effective to transmit voice signals over said line and to reproduce voice signals received over said line, respectively.

7. A telephone system as claimed in claim 6 wherein the frequency rate of said alternating control voltages is less than that of the lowest frequency component in the voice signals transmitted from said station.

8. In a telephone system as claimed in claim 6 wherein said source of alternating current is located at one of said stations, and the system in-

cludes circuit arrangements for continuously transmitting alternating current from said source over said line to the other said station.
